3-ALKOXYCYCLOBUTANOLS
 Edward U. Elam and James C. Martin, Kingsport, Tenn.,
 assignors to Eastman Kodak Company, Rochester, N.Y.,
 a corporation of New Jersey
 No Drawing. Filed Nov. 27, 1964, Ser. No. 414,474
 5 Claims. (Cl. 260—611)

ABSTRACT OF THE DISCLOSURE

The chemical or catalytic reduction of 3-alkoxycyclobutanones provide the corresponding 3-alkoxycyclobutanols. The 3-alkoxycyclobutanols are useful as chemical intermediates for example, in the preparation of carboxylic ester derivatives of the 3-alkoxycyclobutanols, as well as solvents, plasticizers, hydraulic fluids, etc.

DISCLOSURE

This invention relates to novel chemical compounds and their preparation. More particularly, this invention relates to novel 3-alkoxycyclobutanols of the formula:

their preparation by the reduction of 3-alkoxycyclobutanones and to carboxylic acid esters of the 3-alkoxycyclobutanols.

In the above formula for the novel 3-alkoxycyclobutanols of our invention, the substituent R^1 can be hydrogen or lower alkyl and the substituent R^2 is alkyl or aralkyl. The substituents R^3 and R^4 , when taken singly, are alkyl and, when taken collectively with the carbon atom to which they are attached, represent a saturated carbocyclic ring having 4 to 8 ring carbon atoms.

R^1 , when lower alkyl, is typically alkyl of 1 to about 5 carbon atoms such as methyl, ethyl, propyl, isopropyl, butyl, isobutyl, sec-butyl, tert-butyl, n-pentyl, etc. R^2 is typically substituted or unsubstituted alkyl of 1 to about 18 carbon atoms or aralkyl of 7 to about 19 carbon atoms and, when alkyl, is preferably alkyl of 1 to about 8 carbon atoms such as methyl, ethyl, propyl, isopropyl, butyl, isobutyl, pentyl, hexyl, heptyl, octyl, 2-ethylhexyl, etc. R^2 , when aralkyl, is typically benzyl, diphenylmethyl, triphenylmethyl, (p-tolyl)methyl, etc. R^3 and R^4 , when alkyl, are typically alkyl of 1 to 18 carbon atoms and are preferably alkyl of 1 to about 8 carbons such as methyl, ethyl, propyl, isopropyl, butyl, isobutyl, sec-butyl, pentyl, hexyl, octyl, 2-ethylhexyl, etc. R^3 and R^4 , when taken collectively with the carbon atom to which they are attached to represent a saturated carbocyclic ring of 4 to 8 carbon atoms, typically represent carbocyclic rings such as cyclobutylidene, cyclopentylidene, cyclohexylidene, cycloheptylidene, and cyclooctylidene.

Examples of some of the preferred 3-alkoxycyclobutanols of our invention include compounds such as 2,2-dimethyl-3-methoxycyclobutanol; 2,2 - dimethyl-3-ethoxycyclobutanol; 3 - benzyloxy-2,2-dimethylcyclobutanol; 2-butyl-2-ethyl-3-butoxycyclobutanol; 2,2,4 - trimethyl-3-ethoxycyclobutanol; 2,2 - dimethyl-3-(2-ethylhexyloxy)cyclobutanol; 1-ethoxy-3-hydroxyspiro[3.5] - nonane; 3-isobutoxy-2,2-diethylcyclobutanol; 3-benzyloxy-4-ethyl-2,2-dimethylcyclobutanol; etc.

The esters of our invention can be represented by the formulae:

and

5 wherein R^1 , R^2 , R^3 and R^4 are as hereinbefore defined; R^5 is the residue of an organic monocarboxylic acid and R^6 is the residue of an organic diacid.

10 R^5 typically has 1 to about 18 carbon atoms and preferably has 1 to about 8 carbon atoms. Examples of monocarboxylic acid residues represented by R^5 are those from alkanoic acids such as formic acid, acetic acid, propionic acid, butyric acid, isobutyric acid, valeric acid, etc.; unsaturated acids such as acrylic acid, methacrylic acid, oleic acid, etc.; substituted alkanoic acids such as trichloroacetic acid, etc.; and substituted or unsubstituted aromatic acids such as benzoic acid, p-nitrobenzoic acid, etc.

15 R^6 typically has 1 to 18 carbon atoms and preferably contains 1 to about 8 carbon atoms. Examples of diacid residues represented by R^6 are those from acids such as carbonic acid and from organic dicarboxylic acids, e.g., alkanedioic, alkenedioic or arylenedioic acids, such as maleic acid, fumaric acid, succinic acid, adipic acid, phthalic acid, terephthalic acid, isophthalic acid, 3,3'-thiodipropionic acid; etc.

20 Examples of some of the preferred 3-alkoxycyclobutanol esters of our invention include compounds such as 3-ethoxy-2,2-dimethylcyclobutyl acetate; bis(3-ethoxy-2,2-dimethylcyclobutyl) adipate; 3 - ethoxy-2,2-dimethylcyclobutyl decanoate; 3 - methoxy-2,2-dimethylcyclobutyl benzoate; 3 - ethoxy-2,2-dimethylcyclobutyl trichloroacetate; bis(3-ethoxy-2,2-dimethylcyclobutyl) maleate; bis(3-ethoxy-2,2-dimethylcyclobutyl) fumarate; 3-butoxy-2,2-dimethylcyclobutyl ethylcarbonate; 3-methoxy-2,2-dimethylcyclobutyl acetate; 3-ethoxy-2,2-dimethylcyclobutyl p-nitrobenzoate; 3-isobutoxy-2,2-dimethylcyclobutyl methacrylate; 3-ethoxy-2,2-dimethylcyclobutyl acrylate; 3-ethoxy-2,2-dimethylcyclobutyl oleate; bis(3-butoxy-2,2-dimethylcyclobutyl)-3,3'-thiodipropionate; etc.

25 The novel 3-alkoxycyclobutanols of our invention can be prepared by the reduction of a 3-alkoxycyclobutanone. The latter compounds can be prepared by the cycloaddition of a ketoketene and an alkyl vinyl ether. The reaction is carried out, e.g., by heating equimolar amounts of a ketoketene such as dimethyl ketene and an alkyl vinyl ether such as ethyl vinyl ether in an inert polar solvent as illustrated in Martin, U.S. patent application, Ser. No. 276,177, filed Apr. 29, 1963, and now Patent No. 3,312,741.

30 The reduction of the 3-alkoxycyclobutanone can be carried out chemically, i.e., with a chemical reducing agent, or catalytically by hydrogenation of the 3-alkoxycyclobutanone in the presence of a hydrogenation catalyst.

35 When the reduction is carried out chemically, it is preferably performed in a conventional manner with a boron containing chemical reducing agent such as an alkali metal borohydride, an alkoxyborohydride or an amineborane; with an alkali metal hydride such as lithium, sodium or potassium aluminum hydride or with an aluminum alkoxide such as aluminum isopropoxide. Especially preferred as chemical reducing agents are the alkali metal borohydrides, e.g., sodium borohydride. The reduction is preferably carried out in an aqueous medium when an alkali metal borohydride is employed as the reducing agent.

40 In operations of a commercial size, it is preferred to conduct the reduction of the 3-alkoxycyclobutanone catalytically by contacting the 3-alkoxycyclobutanone with hydrogen in the presence of a hydrogenation catalyst. Suitable catalysts include conventional supported and unsupported hydrogenation catalysts such as iron, nickel,

cobalt, ruthenium, palladium, platinum, copper-chromium oxide, etc. Nickel or ruthenium containing hydrogenation catalysts, e.g., Raney nickel or supported ruthenium, are preferred.

The catalytic reduction of the 3-alkoxycyclobutanone is preferably carried out at elevated temperature and super-atmospheric pressure, though temperatures as low as 25° C. and pressures as low as 1 atmosphere are suitable. Suitable temperatures and pressures are from about 25° C. to about 200° C. and about 1 atmosphere to about 300 atmospheres. Preferred temperatures are from about 50° C. to about 150° C. and preferred pressures are from about 10 to about 150 atmospheres.

The following examples illustrate the preparation of the novel compounds of our invention.

Example 1

2,2-dimethyl-3-methoxycyclobutanone (64 g., 0.5 mole) was cautiously added, with cooling in a water bath, to a stirred solution of 10 g. of sodium borohydride in 150 ml. of water. The mixture was stirred overnight at room temperature. The water layer was then saturated with potassium carbonate, the organic material extracted with ether, and the extracts distilled to give 44.7 g. (69% yield) of 2,2-dimethyl-3-methoxycyclobutanol, B.P. 86-88° (16 mm.), n_{D}^{20} 1.4472.

Analysis.—Calcd. for $C_7H_{14}O_2$: C, 64.6; H, 10.8. Found: C, 64.2; H, 10.7.

Example 2

A solution of 200 g. of 2,2-dimethyl-3-methoxycyclobutanone in 300 ml. of methanol was hydrogenated over 20 g. of 5% ruthenium on carbon powder at 100° C., 3000 p.s.i. After reduction was complete, the product was filtered and distilled to give 158.1 g. (74% yield) of 2,2-dimethyl-3-methoxycyclobutanol, B.P. 95-96° C. (25 mm.), n_{D}^{20} 1.4470-1.4472.

Example 3

A solution of 30.5 g. (0.8 mole) of sodium borohydride in 300 ml. of water was stirred vigorously and treated with 280 g. of 2,2-dimethyl-3-ethoxycyclobutanone. An ice bath was used to keep the temperature below 50° C. during the addition. The mixture was stirred at room temperature overnight, and worked up as described in Example 1. The yield of 2,2-dimethyl-3-ethoxycyclobutanol, B.P. 97° C. (22 mm.), n_{D}^{20} 1.4460, was 223 g. (79%).

Example 4

A solution of 250 ml. of 2,2-dimethyl-3-ethoxycyclobutanone in 250 ml. of ethyl alcohol was hydrogenated over 20 g. of 5% ruthenium on carbon at 75° C., 3000 p.s.i. The product was filtered and distilled to give 2,2-dimethyl-3-ethoxycyclobutanol, B.P. 96-97° C. (22 mm.) in 60% yield.

Example 5

A solution of 75 ml. of 2,2-dimethyl-3-ethoxycyclobutanone in 75 ml. of ethanol was hydrogenated over 10 g. of Raney nickel at 100° C., 3000 p.s.i. The yield of 2,2-dimethyl-3-ethoxycyclobutanol, B.P. 97-98° (25 mm.) was 70%.

Example 6

The reduction was carried out according to the above equation as described in Examples 1 and 3 using 3-benzyl-2,2-dimethoxy-2,2-dimethylcyclobutanone. 3-benzyl-2,2-dimethylcyclobutanol boiling at 173-4° C. (25 mm.) n_{D}^{20} 1.5160 was obtained.

Example 7

Under the general conditions of Example 2, the following cyclobutanones are reduced to the corresponding cyclobutanols:

	Cyclobutanone	Cyclobutanol
30	$\text{C}_2\text{H}_5\text{O}-\text{C}(\text{CH}_3)_2-\text{O}$	$\text{C}_2\text{H}_5\text{O}-\text{CH}(\text{CH}_3)_2-\text{OH}$
35	$\text{C}_2\text{H}_5\text{O}-\text{C}(\text{CH}_3)_2-\text{O}$	$\text{C}_2\text{H}_5\text{O}-\text{CH}(\text{CH}_3)_2-\text{OH}$
40	$\text{C}_2\text{H}_5\text{O}-\text{CH}(\text{CH}_2\text{O}-\text{C}(\text{CH}_3)_2)-\text{O}$	$\text{C}_2\text{H}_5\text{O}-\text{CH}(\text{CH}_2\text{O}-\text{C}(\text{CH}_3)_2)-\text{OH}$
45	$\text{C}_2\text{H}_5\text{O}-\text{C}(\text{CH}_2\text{O}-\text{C}_6\text{H}_5)-\text{O}$	$\text{C}_2\text{H}_5\text{O}-\text{CH}(\text{CH}_2\text{O}-\text{C}_6\text{H}_5)-\text{OH}$
50	$\text{C}_2\text{H}_5\text{O}-\text{C}(\text{CH}_2\text{O}-\text{C}_6\text{H}_5)-\text{O}$	$\text{C}_2\text{H}_5\text{O}-\text{CH}(\text{CH}_2\text{O}-\text{C}_6\text{H}_5)-\text{OH}$

The 3-alkoxycyclobutanols of our invention are particularly useful as chemical intermediates, e.g., for the preparation of esters of 3-alkoxycyclobutanols. The novel carboxylic acid esters, of the 3-alkoxycyclobutanols are prepared by conventional esterification methods. The esterification can be carried out by contacting the 3-alkoxycyclobutanol with a carboxylic acid, an acid halide of a carboxylic acid or a carboxylic acid anhydride, preferably in the presence of an acidic or basic esterification catalyst. A preferred method for preparing the novel esters of our invention is to contact the 3-alkoxycyclobutanol with an acid halide, e.g., an acid chloride, in the presence of a tertiary amine, e.g., pyridine.

Another preferred method for the preparation of the esters is to contact the 3-alkoxycyclobutanol with the carboxylic acid in the presence of an aryl sulfonic acid, e.g., p-toluenesulfonic acid.

The following examples illustrate the preparation of the novel carboxylic acid esters of 3-alkoxycyclobutanols of our invention.

5

Example 8

A mixture of 71 g. of 2,2-dimethyl-3-ethoxycyclobutanol, 100 ml. of acetic acid, 100 ml. of toluene, and 0.5 g. of p-toluenesulfonic acid was refluxed under a Dean-Stark trap until no more water came over. The product was treated with 5 g. of potassium acetate and distilled to give 76 g. of 2,2-dimethyl-3-ethoxycyclobutyl acetate, B.P., 95-101° C.

Example 9

A mixture of 100 g. of 2,2-dimethyl-3-ethoxycyclobutanol, 200 ml. of benzene, and 80 g. of pyridine was placed in a flask which was equipped with a stirrer, reflux condenser, and dropping funnel, and 65 g. of adipyl chloride was added slowly. The mixture was stirred three hours and filtered. The solid (pyridine hydrochloride) was washed with benzene; the combined filtrates were washed with water, stripped of solvent, and distilled in a cyclic falling film molecular still to give 63 g. of bis(2,2-dimethyl-3-ethoxycyclobutyl)adipate, B.P. 82-94° (25μ), n_D²⁰ 1.4568-1.4570.

Analysis.—Calcd. for C₂₂H₃₈O₃: Sapon. equiv., 198. Found: Sapon. equiv., 195.

6

Example 10

A mixture of 71 g. (0.5 mole) of 2,2-dimethyl-3-ethoxycyclobutanol, 103 g. (0.6 mole) of decanoic acid, 100 ml. of toluene, and 2 g. of p-toluenesulfonic acid was refluxed under a Dean-Stark trap until all of the water had been removed. The product was stripped of solvent and the residue distilled in a cyclic falling film molecular still to give 2,2-dimethyl-3-ethoxycyclobutyl decanoate, B.P. 85° (70μ), n_D²⁰ 1.4460.

Analysis.—Calcd. for C₁₈H₃₄O: Sapon. equiv., 298. Found: Sapon. equiv., 289.

Example 11

A solution of 13 g. of 3-methoxy-2,2-dimethylcyclobutanol in 150 ml. of pyridine was treated with 15 g. of benzoyl chloride. The mixture was allowed to stand overnight, filtered from precipitated pyridine hydrochloride, and washed with water. The solvent was evaporated on the steam bath. The residue (23 g.) had n_D²⁰ 1.5081. It was determined to be very pure by gas chromatography.

Example 12

Under the general conditions of Example 11, the following cyclobutanols and acid halides give the products shown:

Cyclobutanol	Acid Halide	Product
	Cl ₂ C(=O)CCl	
	ClC(=O)CH=CHCOCl	
	ClC(=O)OC ₂ H ₅	
	BrC(=O)CH ₃	
	ClC(=O)c ₆ H ₄ NO ₂	
	ClC(=O)C(=CH ₃)CH ₃	

Cyclobutanol	Acid Halide	Product

Example 13

A mixture of 72 g. (0.5 mole) of 3-ethoxy-2,2-dimethylcyclobutanol, 500 ml. of benzene, 72 g. (1 mole) of acrylic acid, 1 g. of hydroquinone monomethyl ether and 5 g. of p-toluenesulfonic acid was refluxed under a 6-in. Vigreux column equipped with a Dean-Stark water trap. After water removal was complete, the solution was washed with water, 10% sodium carbonate solution, water and dried over anhydrous sodium sulfate. This solution was distilled from cuprous chloride through a 6-in. Vigreux column to give 80.2 g. of 3-ethoxy-2,2-dimethylcyclobutyl acrylate, B.P. 80-83° C. (5 mm.).

The novel 3-alkoxycyclobutanols are useful, not only for the preparation of esters, but also as solvents, plasticizers, e.g., for vinyl resins, hydraulic fluids, etc. The 3-alkoxycyclobutanol esters of unsaturated acids are useful in the preparation of copolymers with other unsaturated compounds and the 3-alkoxycyclobutanol esters with saturated carboxylic acids are useful as plasticizers, solvents, etc.

The following example illustrates the use of one of the esters of our invention as a plasticizer for a vinyl halide resin.

Example 14

A plastic composition containing 66 parts of bis(2,2-dimethyl-3-ethoxycyclobutyl) adipate in polyvinyl chloride was prepared by milling the components together on heated rolls. The resulting plastic was tough, flexible and had good mechanical properties.

The following example illustrates the preparation of a copolymer containing one of the esters of our invention.

Example 15

A copolymer containing 30% 3-ethoxy-2,2-dimethylcyclobutyl acrylate and 70% acrylonitrile was prepared by conventional polymerization techniques. It had a sticking temperature of 160° C. and could be cast into tough films and spun into strong fibers.

Although the invention has been described in detail with particular reference to certain preferred embodiments

thereof, variations and modifications can be effected within the spirit and scope of the invention as described hereinbefore and as defined in the appended claims.

We claim:

1. A compound having the formula:

wherein:

25 R¹ is selected from the group consisting of

- (a) hydrogen and
- (b) lower alkyl;

R² is selected from the group consisting of

- (a) alkyl of 1-18 carbon atoms and
- (b) aralkyl of 7-19 carbon atoms;

30 R³ and R⁴, when taken singly, are alkyl of 1-18 carbon atoms and, when taken collectively with the carbon atom to which they are attached, represent a saturated carbocyclic ring of 4 to 8 ring carbon atoms.

2. A compound having the formula

wherein:

35 R¹ is selected from the group consisting of

- (a) hydrogen and
- (b) lower alkyl;

R² is selected from the group consisting of

- (a) alkyl of 1 to 8 carbons and
- (b) aralkyl of 7 to 19 carbons;

40 R³ and R⁴, when taken singly, are alkyl of 1 to 8 carbons and, when taken collectively with the carbon atom to which they are attached, represent a saturated carbocyclic ring of 4 to 8 ring carbon atoms.

3. 3-methoxy-2,2-dimethylcyclobutanol.

4. 3-ethoxy-2,2-dimethylcyclobutanol.

5. 3-benzyloxy-2,2-dimethylcyclobutanol.
